UNITED STATES PATENT OFFICE

ADOLPH LANGSNER, OF CHICAGO, ILLINOIS, ASSIGNOR TO EUGENE DIETZGEN CO., OF CHICAGO, ILLINOIS, A CORPORATION OF DELAWARE

PRINTING APPARATUS

Application filed January 11, 1930. Serial No. 420,170.

This invention relates to the photoprinting art; and more especially to improvements in printing apparatus and machines, and to simplified methods of use.

5 The main objects of the invention are to provide an improved form of photoprinting machine as a whole; to provide for numerous new and useful details in the construction and operation of such machines; to provide especially for certain operating parts of improved form and simplified construction; to provide better means for controlling the movement of the light generating member; to provide improved electrical features; to provide a better time element control mechanism; to provide an improved form of take-up for the flexible cable which supplies current to the lamp; to improve the structure and control of the work-holding wrapper or curtain and its 15 roller mechanism; and to provide for ready assembly and renewal of parts.

An illustrative embodiment of this invention is shown by the accompanying drawings, in which:—

Figure 1 is a front elevation of the device shown in Fig. 3, part being broken away to show certain details of construction, and the light generator being shown in its raised position, ready for descent.

Fig. 2 is a side elevation of the device as viewed from the left of Fig. 3.

Fig. 3 is an enlarged plan of the device.

Fig. 4 is a section on the line 4—4 of Fig. 1.

Fig. 5 is a greatly enlarged vertical fragmentary section of the upper end of the curtain roll and associated parts, on the line 5—5 of Fig. 3.

Fig. 6 is an enlarged elevation of the speed control clamping and gear means as viewed in Fig. 2.

Fig. 7 is mainly a section on the line 7—7 of Fig. 6.

Fig. 8 is mainly a side view of the lamp unit as viewed from the right of Fig. 3.

Fig. 9 is a conventional diagram of the lamp controlling lines, pulleys and counterpoise, set ready for operation.

Fig. 10 is an enlarged view of the lamp propelling weight as viewed from the left to 50 Figs. 1 and 4.

Fig. 11 is an enlarged fragmentary vertical section on the line 11—11 of Fig. 2.

Fig. 12 is a detail showing the take-up for the lamp cable when the lamp is raised.

Fig. 13 is a section on the line 13—13 of 55 Figs. 3 and 6.

Fig. 14 is a plan of the forward dashpot shown on Fig. 3, and the associated control means.

In the construction shown in the drawings, the device as a whole comprises mainly a frame 1, a transparent platen 2 mounted thereon to receive the copy work, a retractable wrapper mechanism 3 to hold the work in place, a movable light unit 4, operating 60 mechanism designated generally by numeral 5 for said light unit, and electrical supply and control means designated 6 to supply current to the lamp.

The frame 1 comprises mainly a pair of 70 upright lateral supports 7, in combination with a pair of vertically spaced horizontal peripheral bars 8 and 9, each of semicircular shape in front and extending across somewhat convexly at the back. These bars are 75 right angular in cross section with their upright flanges convergent and with their horizontal flanges disposed outwardly. The members 7 each have spaced feet 10 and 11 to support the machine uprightly, which feet 80 are adapted for anchoring to the floor if desired.

The glass platen 2 is vertically straight and horizontally arcuate with its side edges disposed rearwardly against the uprights 12 and 85 13 of frame 1; and it rests on the forward part of the lower bar 8, the upper edge being embraced and held by the corresponding part of the similar upper bar 9. The frame is open at the back, top and bottom. 90

The work-holding mechanism 3 comprises a flexible curtain or wrapper proper 14 which is retractably extensible over the outward face of the platen 2 for releasably securing the subject matter to be printed, interposed 95 between the photosensitive sheet and the platen, as will be understood.

The right-hand edge of curtain 14 is secured to the corresponding upright 12, as viewed in Fig. 4, and its opposite edge is se- 100

cured to a roller 15 whereon the curtain winds and unwinds to the right and left respectively as the roller travels accordingly, to and fro, over the face of the platen.

The ends of roller 15 have winding drums 16 pivoted thereon for cords 17 which are wound differentially relative to the curtain and serve to maintain the roller uprightly between the forward flanges 18 on the angle bars 8 and 9. Each cord 17 has one end secured to the left side of frame 1 and its opposite end secured to its respective drum 16. In order that the effective rolling diameters for the cords and of the curtain shall always be substantially alike, the drums 16 are formed conoidally with spiral grooves 19 to receive the cords 17 which are fastened at or adjacent to the large outer ends of the spirals, as at 20. See Fig. 5. When the curtain is unrolled, the effective diameter of the roll decreases, and likewise the diameter of the corresponding part of each cord winding decreases as it winds spirally toward the apex of the drum. The curtain 14 and cords 17 are kept in tension by reaction of the adjustable spring 21 between the drums 16 and the ends of roller 15 respectively. Said springs 21 are tensioned by means of the mutually engaging ratchet members 22 and 22' fixed on the drums 16 and the spring supporting pins 23 carried by the roller 15 respectively.

The metallic strips, or bands, 24 serve doubly as tracks for the cord drums 16 to roll upon and as binders to secure the platen 2 in place against bars 8 and 9. They also protect the glass from contact with the metallic drums 16. The platen is furthermore protected by felt backing strips 25 interposed between the glass and the convergent bar flanges 18'. See Figs. 5 and 11.

The light unit or lamp 4 comprises a source of actinic rays, preferably concentrated, as indicated at 26 on the arc lamp of Fig. 8. Said lamp is movable lengthwise of the platen 2 and about coaxially thereof, as will be more fully explained.

The operating mechanism 5 for said lamp comprises a supporting cord 27 which passes over a pulley 28 on the frame supported arm 29, thence downwardly to the pulley 30, shown at the left on Fig. 1, and finally down to the counterpoise 32. The operation of cord 27 and weight 32 is coordinated with a secondary cord 33 and a damping mechanism 34 having a dashpot mode of operation. The cord 33 is mechanically belt like and rides on a pair of pulleys 36 and 37 at the top and bottom respectively. This belt is held in resilient tension by means of a series connected spring helix 38 housed in the weight 32 which is hollow. One end of cord 27 and the counterweight end of cord 33 are secured to weight 32 at 39 and the other end of cord 33 passes through a hole in the top of said weight

and is connected to the upper end of spring 38, the lower end of the latter being fastened to the bottom of said weight, as at 40. Said cord 33, adjacent to fastening 39, passes through the helix 38. See Fig. 10.

The upper pulley 36 is connected operatively as by integral construction, with a duplex damping mechanism 34, comprising a pair of dashpots 43 and associated mechanism to be described. Said dashpots are rigidly connected in spaced parallel relation and each includes a cup 45, piston 46 and rod 47. The rods 47 are connected to crank arms 48 arranged in quadrature on shaft 49, (see Fig. 6) which carries a loose pinion 50 coturnably connected to said shaft by a spiral spring 51 for cushioning the coupling torsion. Said pulley 36 is combined structurally with a gear wheel 53 which coacts with the relatively small pinion 50. The effect of the multiplying gear 50—53 is to cause the damper as a whole to operate many times successively as a duplex pump substantially for each descent of the lamp.

The dashpots 44 are adjustable by means of a common rotary valve shaft 55 coacting with the ports 56 in the closed ends of cups 45. See Figs. 6 and 13. Said shaft 55 has a crank handle 58 which swings past an index scale 59 on the face of one of the cups, as shown in Fig. 6. The compression spring 60 assures sufficient contact friction between valve 55 and its support to cause the valve to remain set at any desired adjustment or degree of registry of the passageways 56 and 61. The said damper mechanism is all formed with or mounted on a special integrally cast frame 62 therefor, which is secured to upright 12 and to the lower part of the arm 29.

The tension of belt 33 is such that the operator may quickly push the counterpoise 32 down for setting the device ready for service, without operating the dashpots, the belt 33 slipping idly over the pulley 36, and the cord 27 lifting lamp 4. During the printing operation, the movement is in accordance with the arrows on Fig. 9.

An arm 63 extends backwardly from the casing of lamp 4 and slidably engages an upright guide rod 64 fixed on frame 1.

The electrical supply and control means 6 comprises mainly a flexible duplex cable 65 leading to the lamp 4 from an automatic unit toggle switch 66 in the lower back part of the frame. From said switch the circuit leads through a rheostat housed in box 67 and thence to any available source of current. The switch 66 may be of any appropriate type for reciprocating action to open and close. Referring to Figs. 1, 4 and 9 said switch has a forked toggle member or arm 68 controlled by a button 69 on cord 33 to open the switch when the lamp has descended throughout its course. A restoring spring 71 serves to close

said switch whenever the lamp 4 and button 69 are raised. The button 69 is frictionally engaged on cord 33 and may be adjusted manually along the length of said cord, so as to open switch 66 at any desired position of the lamp in its descent. After said button has opened the switch, it may slide on its cord so as not to interfere materially with the continued descent of the lamp. The arc 10 lamp 4 is of usual design.

In order to take up the slack in the electric cable 65 when the lamp 4 is raised, a series of rings 75, or the like, are attached to the cable in spaced relation to each other, and 15 with the hoist line 27 threaded therethrough, as shown in Figs. 1 and 12.

In using the device herein described, the operator first rolls the curtain back to the right and then applies the work to be printed 20 to the exterior of the platen. He then rolls the curtain roller to the left and thereby secures the work snugly in place. Said roller may be controlled by the knees, leaving the hands free to adjust the work, that is to say, 25 the tracings or the like and the sensitized paper. The roller tends to remain wherever left by the operator. The lamp is then raised by downward pressure of the hand on weight 32. This causes the belt 33 to slide over pulley 30 36 and releases the button 69 from switch 66 which then closes and lights the lamp 4.

In operation, the light unit 4, being heavier than the counterpoise 32, gradually descends back of the platen, subject to the retarding 35 control of the damper mechanism 34. If the work is of a kind to print quickly, the damper valves are opened wider; but if slowly, the valves are more or less closed, so as to assure the correct time element and corresponding 40 degree of printing.

Although but one specific embodiment of this invention is herein shown and described, it is to be understood that numerous details may be altered or omitted without departing 45 from the spirit of the invention as defined by the following claims:

I claim:

1. In a photo-printing apparatus having a movable lamp, means for controlling the 50 speed of said lamp comprising a pair of vertically disposed and integrally framed asynchronous reciprocating dashpots operatively connected thereto for actuation thereby and gear mechanism interposed to speed up the dashpots, said gear including a spring coupling to cushion the torsional stress.

2. A photo-printing apparatus comprising a transparent platen to receive the work, a lamp in printing relation thereto and movable 55 parallelly with said platen, damping means to regulate the speed of such movement comprising a reciprocating dashpot operatively connected to said movable lamp and actuated thereby and having a gear mechanism interposed to cause rapid reciprocation

of said dashpot, said gear mechanism including a yieldable coupling to cushion the tractive stress, and a direct leverage manual controller to adjust said damping means.

3. A photo-printing apparatus comprising 70 a work receiving platen, a lamp in movable printing relation thereto, multiple dashpot damping means to retard such movement, means to multiply the speed of oscillation of the dashpots, said means including a yieldable coupling adapted to cushion the initial tractive stress, and a direct leverage controller to adjust said damping means.

4. A photo-printing apparatus comprising 80 a transparent and arcuate work receiving platen, a longitudinally movable source of light back of said platen, and duplex adjustable dashpot means geared to control the speed of said light source, the gearing including 85 a torsionally acting spring coupling to cushion the tractive stress.

5. In a photo-printing apparatus having a movable electric lamp, means for controlling the circuit to said lamp comprising a 90 unit toggle switch having an extended toggle member, a belt operatively connected to said lamp for actuation thereby, and means on said belt arranged to engage said toggle member after a predetermined movement of said lamp.

6. A photo-printing apparatus comprising 95 a work receiving platen, a lamp in movable printing relation thereto, a belt suspending said lamp, a gear actuated by the movement of said belt, a dashpot damping mechanism 100 actuated by said gear to control the movement of said lamp, a unit toggle switch having an extended forked toggle member, said belt being arranged to pass between the fork arms of said toggle member, and adjustable 105 means secured to said belt to directly actuate said toggle member according to a predetermined movement of said belt.

7. A photo-printing apparatus comprising 110 a work receiving platen, a lamp in movable printing relation thereto, a belt suspending said lamp, a gear actuated by the movement of said belt, a crank driven multiple dashpot mechanism actuated by said gear to multiply 115 the speed of oscillation of the dashpots and to control the movement of said lamp, a unit toggle switch having an extended forked toggle member, said belt being arranged to pass between the fork arms of said toggle member, and means secured adjustably to said belt to 120 directly actuate said toggle member.

Signed at Chicago this 8th day of January, 1930.

ADOLPH LANGSNER.
